STAND FOR CORDLESS ELECTRIC IRONS

John P. Walpole, Jackson Heights, N. Y.

Application October 11, 1935, Serial No. 44,602

5 Claims. (Cl. 219—25)

This invention relates to pressing irons and such electrically heated devices and the receptacles and stands for same, the arrangement of which provides for the heating of the iron while 5 on the stand, the electric coupling of which is disconnected coactively with the removal of the iron from the stand so that the ironing may be accomplished without the usual encumbering extension cord.

10 The general object of my invention is to provide a novel arrangement of a pressing iron base or stand particularly adapted for economic manufacture, a novel form of which will facilitate the placement of the iron on the stand without requiring the lifting of the iron and in such manner as to assure the positive coupling of the connector prongs into the plug receptacle on the base with comparative ease.

Another object of my invention is to provide 20 a device of the character indicated having guiding means by which the pressing iron is guided onto the stand, which means may be readily adjusted laterally, thereby adapting the stand for use in conjunction with irons of various widths.

25 A further object of my invention is to provide a novel form of adapter plug which will facilitate the use of the standard pressing iron in conjunction with my improved ironing stand.

The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therein as do not affect the spirit of the invention nor exceed the scope thereof as expressed in the appended claims.

In the drawing:

Fig. 1 is a side elevational view of my improved electric iron stand with the pressing iron in place on the same.

45 Fig. 2 is a plan view of my iron stand without the pressing iron.

Fig. 3 is a cross-sectional view of the stand taken on line 3—3 of Fig. 2.

50 Fig. 4 is a front end elevation of a typical pressing iron adapted for use in cooperation with my stand.

Figs. 5, 6, and 7 illustrate the adapter plug of my invention by which a standard iron may be converted for use with my ironing stand, Fig. 5

being a side elevation of an iron with the adapter in place, Fig. 6 a plan sectional view taken on line 6—6 of Fig. 5, and Fig. 7 being an exploded perspective view of the adapter apart from the iron.

5 Reference is now directed to the accompanying drawing for a more detailed description thereof. The base or stand of my invention indicated by numeral 8 embodies a plate-like structure having adjacent each longitudinal edge an up-standing flange 9. Opposed sides of the flanges 9 converge upwardly so as to function as a guide when the pressing iron 10 is slid into place on the stand 8.

My invention is intended for use in conjunction 15 with the usual form of pressing iron, a front elevation of which is shown in Fig. 4. Many of the pressing irons now in use are equipped with a bottom plate 11, the edges of which are flared outwardly. The function of the flanges 9 in addition 20 to acting as a guide is also to engage with the flared edges of the plate 11 in a manner to prevent the removal of the iron 10 from the stand 8 by lifting the iron. The area of the stand 8 25 between the flanges 9 is formed in substantially sharp corrugations, the upper portions of which present longitudinal ribs 12 over which the iron 10 may be readily slid with a minimum of resistance.

The forward portion of my iron stand 8 indicated by numeral 13 is inclined downwardly and has its edge arcuately formed, thus presenting a lip onto which the pressing iron 10 may be conveniently slid. The forward ends of the flanges 9 are flared outwardly, thereby facilitating the entrance of the iron into the guiding surfaces of the flanges. The longitudinal sides of the stand 8 beyond the flanges 9 are flared outwardly to a thin edge flush with the periphery of the lip 13. In the mentioned flared edges suitable holes 14 are 30 provided thru which screws may be inserted to permanently attach my stand to an ironing board. The corrugated portion 12 is disposed slightly 35 above the bottom of the stand 8 so that the lower edges of the corrugations are spaced from the ironing board thereby assuring ample dissipation 40 of the heat given off by the iron.

The rear portion of my iron stand 8 is dished upwardly to form a hollow upstanding structure 15 into which is suitably constructed a plug receptacle 16. The plug receptacle 16 is provided with the usual plug connectors 17, each of which are connected respectively to conductors of the extension cord 18. The free end of the latter is equipped with the usual connector plug 19 which 55

may be plugged into electric house service in the usual manner.

The rear end of the pressing iron 10 is equipped with a pair of terminal prongs 20, which prongs are connected to the terminal ends of the heating element of the iron 10. The prongs 20 project horizontally from the rear of the iron 10 and are disposed to engage in the plug connectors 17 during the rearward sliding of the iron 10. In this fashion the heating element of the iron is subjected to the electric current while the iron is disposed on the stand 8.

As aforementioned, my iron stand 8 may be adjusted to fit various widths of pressing irons. For this purpose the adjustment screw 22 is provided, which screw is inserted thru apertures cut in the sides of the corrugations 12. The ends of the screw 22 are threaded respectively right and left hand, which ends engage in threaded sleeves 23 secured to the underside of the outermost corrugation 12 and adjacent the respective flanges 9. In order to provide sufficient resilience to permit the required adjustment of the rear portion of the flanges 9 the base 8 is slotted at each side, as shown at 24, adjacent the forward surface of the structure 15. The slots 24 extend inwardly to include one or more of the outer corrugations 12.

One end of the screw 22 is provided with a square head 22', which may be engaged by a suitable key inserted thru the aperture 25 by which the screw 22 may be rotated in either direction to effect the separation or moving toward each other of the rear end of the flanges 9 so that the latter will substantially fit the particular iron to be used.

Reference is now directed to Figs. 5, 6, and 7, wherein is illustrated an adapter plug enabling the use of a standard iron 26 in conjunction with the iron stand 8 heretofore described. The connection to the heating element of the standard iron is effected thru a pair of upstanding terminal prongs which are generally protected by a sheath 27.

The body 28 of my adapter is substantially 45 goose-neck in shape comprising component halves to facilitate the assembly of the unit. In the forward portion 29 of the adapter is housed a pair of plug connectors so arranged as to be readily coupled onto the usual terminal prongs disposed 50 in the sheath 27. From the rear portion 30 of the adapter projects a pair of connector prongs 31, which prongs project horizontally and are disposed to be readily inserted in the plug connectors 17 shown in Fig. 3.

The permanent attachment of my adapter 28 to the standard iron 26 as well as the assembly of the body of the adapter is effected by a pair of clamp plates 32, each shaped to fit snugly onto the longitudinal sides of the adapter. The forward 60 portions of the plates 32 are cambered to fit over the sides of the sheath 27 so that after installation of the clamp screw 33 the adapter unit is held securely in place on the iron 26.

What is claimed as new is:

1. The combination of a pressing iron with a stand for supporting the iron, an electric socket carried by said stand, prongs connecting said iron electrically with said socket, said stand comprising an intermediate area corrugated longitudinally and having up-standing flanges bordering

said corrugated area and extending inwardly to function as guides for the iron in aligning the prongs thereof with said socket, said corrugated area being laterally resilient to permit movement of said bordering flanges to accommodate said pressing iron. 5

2. The combination of a pressing iron with a stand for supporting the iron, an electric socket carried by said stand, prongs connecting said iron electrically with said socket, said stand comprising an intermediate area corrugated longitudinally and having up-standing flanges bordering said corrugated area and extending inwardly to function as guides for the iron in aligning the prongs thereof with said socket, said corrugated area being laterally resilient to permit adjustment of said bordering flanges to accommodate said pressing iron, and adjustment means adapted to expand or contract with said corrugated area for fixing the position of said flanges relative to said 20 pressing iron. 10

3. The combination of a pressing iron with a stand for supporting the iron, an electric socket carried by said stand, prongs connecting said iron electrically with said socket said stand comprising an intermediate area corrugated longitudinally and having up-standing flanges bordering said corrugated area and extending inwardly to function as guides for the iron in aligning the prongs thereof with said socket, said corrugated area being laterally resilient to permit adjustment of said bordering flanges to accommodate said pressing iron, and adjustment means adapted to expand or contract said corrugated area for fixing the position of said flanges relative to said 25 pressing iron, said adjustment means comprising a threaded rod threadedly engaging said flanges and passing laterally thru said corrugated area 30 so as to reinforce same. 35

4. A stand for support of a pressing iron, adapted for fabrication of a single piece of sheet material and comprising an intermediate area corrugated longitudinally, said corrugations being transformed into a flat lip at the forward end of said stand and having upstanding longitudinal 45 flanges bordering said corrugated area, said sheet material being dished upwardly at the rear end of said stand to form a hollow upstanding structure for housing a plug receptacle therein, said intermediate area being laterally resilient to permit movement of said bordering flanges. 50

5. A stand for support of a pressing iron, adapted for fabrication of a single piece of sheet material and comprising an intermediate area corrugated longitudinally, said corrugations being transformed into a flat lip at the forward end of said stand and having up-standing longitudinal flanges bordering said corrugated area, said sheet material being dished upwardly at the rear end of said stand to form a hollow up-standing structure 60 for housing a plug receptacle therein, said intermediate area being laterally resilient to permit movement of said bordering flanges, and adjustment means adapted to position said flanges so as to fit the sides of a pressing iron, said adjustment 65 means comprising a threaded rod threadedly engaging said flanges and passing laterally thru said corrugated area so as to reinforce same. 65
